CLAIM

The ornamental design for a smart band, as shown and described.

DESCRIPTION

1.1 is a front elevation view of a smart band showing our new design;

1.2 is a back elevation view thereof;

1.3 is a left side elevation view thereof;

1.4 is a right side elevation view thereof;

1.5 is a top plan view thereof;

1.6 is a bottom plan view thereof; and

1.7 and 1.8 are two perspective views thereof.

(Continued)

The broken lines in FIG. 1.6 depict portions of the smart band that form no part of the claimed design.

1 Claim, 6 Drawing Sheets
